UNITED STATES PATENT OFFICE.

CHARLES F. HELFLINGER, OF HOBART, WASHINGTON.

STOVE-DOOR KNOB.

1,161,669.

Specification of Letters Patent. Patented Nov. 23, 1915.

Application filed June 3, 1915. Serial No. 32,007.

To all whom it may concern:

Be it known that I, CHARLES F. HELFLINGER, a citizen of the United States, and a resident of Hobart, in the county of King 5 and State of Washington, have invented a new and Improved Stove-Door Knob, of which the following is a full, clear, and exact description.

My invention relates to a knob adapted 10 to be applied to standard makes of stove doors.

The prime object of my invention is to provide a knob of the indicated character, so formed and arranged as to be effectively 15 insulated from the metal parts of the stove and door to prevent the undue heating of the knob.

A further object of the invention is to so form the knob that the body thereof will 20 radiate the heat imparted thereto and thereby further minimize the tendency of the gripping portion of the knob to become heated.

The invention also has for its object to 25 provide a knob of the indicated character, of simple construction and arranged to be conveniently applied.

The invention will be particularly explained in the specific description following.

Reference is had to the accompanying drawings forming part of this specification, in which similar characters of reference indicate corresponding parts in all the views, 35 and in which:

Figure 1 is a horizontal section showing my improved knob applied; Fig. 2 is a side elevation thereof, as applied to a stove door; and Fig. 3 is a partly sectional plan view 40 showing the device applied to a door of a different form from that illustrated in Fig. 1.

The invention is applicable to a door A¹ of any ordinary stove A having a bolt hole 45 for the reception of a bolt to secure a door knob in position.

My improved knob comprises a base plate 10 having a hole therethrough for the passage of a stove bolt 11. Surrounding the 50 bolt is an asbestos sleeve 12, which, when in position in the bolt hole of the door A¹, constitutes a bushing. At each end of the asbestos sleeve 12 are asbestos washers 13, 13^a, here shown as flanges integral with the

sleeve 12. The base 10 is preferably received on a noncircular portion 11^a of the bolt 11, and a second washer 13^b is provided on the bolt outside of the base 10 beneath the nut 11^b thereof. Thus the base 10 is effectively insulated from metallic contact 55 with the door A¹. It is to be understood that the knob may be otherwise secured, as will appear. In the form shown in Fig. 1, the bolt is of the type having a lateral catch 14 turning therewith to engage at the inside 60 of the stove A adjacent to the door opening.

From the base 10 the knob extends forwardly in the form of two side arms 15, and these are converged and are brought parallel near their outer ends and are united by 65 rivets 16^b, or equivalent means. Formed upon or secured to the outer ends of the arms 15 are grip members 17 which are return bent and are thus disposed in a rearward direction at each side of the arms 15, and 70 are spaced from the latter so that there will be a circulation of air around the gripping members. The returned portions of the gripping members, designated generally by 75 the numeral 18, are adapted to be grasped 80 between the fingers of a person manipulating the knob and stove door. Said gripping members have a covering of asbestos, thereby providing an intermediate metal portion 19 and layers 20, 21, of asbestos.

By the described construction the base of the knob and its securing bolt are insulated from the stove door and a circulation of air around the gripping members is assured, together with an insulation of said gripping 85 members, the whole contributing to minimize the undue heating of the contact surfaces of the gripping members.

In the form shown in Fig. 3, the knob, except as to its securing bolt, is the same 90 as in Fig. 1, there being the same base 10 and arms 15 united by rivets 16, or the like to the gripping members 17 and having insulated return members 18. In this figure the device is shown applied to that type of 100 stove door A² having an integral latch projection 14^a adapted to engage a lug a on the stove. The bolt 11^c in this form is a short bolt and the sleeve 12^a is correspondingly shortened and provided with insulating washers or flanges 13^c, 13^d for insulating the bolt 11^c and its nut 11^d, the additional washer 13^e corresponding with the washer 105

13^b being also preferably employed. The returned gripping members 18 may be rigidly connected by a brace 22, which extends transversely between the same, and through the arms 15.

Having thus described my invention, what I claim as new and desire to secure by Letters Patent, is:

- 10 1. A knob of the character described, including a base, a body extending forwardly from the base, and arms forming gripping members at the outside of the body and secured to the same near the outer end thereof, said gripping members extending rearwardly toward the base and spaced from the body, and means whereby to secure the knob in position, there being a transverse element rigidly connecting the said gripping mem-
- 15

bers and extending between the same and through the body.

2. A knob of the character described, including a base, a body extending outwardly from the base and gripping members on the outer end of the body, said members extending rearwardly along the opposite sides of the body and spaced from the latter, the rear ends of said gripping members being free from the body and base.

In testimony whereof I have subscribed my name to this specification in the presence of two subscribing witnesses.

CHARLES F. HELFLINGER.
